His Attorney

UNITED STATES PATENT OFFICE.

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRACK CIRCUIT APPARATUS.

Application filed October 7, 1926. Serial No. 140,009.

My invention relates to railway track circuit apparatus, and has for an object the provision of means for improving the operation of track relays.

5 I will describe three forms of apparatus embodying my invention, and will then point out the novel features thereof in claims.

In the accompanying drawing, Fig. 1 is a diagrammatic view showing one form of apparatus embodying my invention. Figs. 10 2 and 3 are views showing modifications of the apparatus shown in Fig. 1 and also embodying my invention.

Similar reference characters refer to similar parts in each of the several views.

Referring first to Fig. 1, the reference characters 1 and 1^a designate the track rails of a railway which are divided by insulated joints 2 to form a track section A—B. This 20 section is provided with a track circuit comprising a source of current connected across the rails at one end and a track relay R having a winding connected across the rails at the other end. As here shown, the source 25 of track circuit current is a track transformer T having its secondary 3 connected across the rails through a limiting reactance 8, and having its primary 4 constantly supplied with alternating current from a transmission line 5. The relay R comprises a 30 winding 6 connected across the rails 1 and 1^a, and a second winding 7 constantly supplied with alternating current from a transformer L which in turn is energized from the transmission line 5.

35 Located at the transformer end B of section A—B is a floating relay F which is connected across the track rails 1 and 1^a, so that this relay is normally energized. Interposed between the winding of relay F and the lower track rail 1^a is an impedance 9 which, as here shown, is a resistance. When the 40 relay F is closed, this impedance 9 is shunted by a low resistance path including a front contact 10 of relay F.

45 I have observed that when the floating relay F is connected directly across the track rails in accordance with standard practice, and when a train is in the section moving toward the floating relay, this relay will open when the train reaches a certain point in the section. The train shunt may then become of higher resistance, however, due, for example, to the condition of one or both of

the track rails, and may therefore, allow 55 the front contacts of the floating relay to again close. As the train proceeds toward the floating relay, the shunt resistance will again become lower, so that this relay will again open its front contacts. This action 60 of the floating relay may be termed "bobbing". When, however, the floating relay is connected with the rails in the manner shown in Fig. 1, the relay will remain open after it once opens, because the impedance 65 9 is then effective to materially reduce the amount of current supplied to the relay. Conversely, when a train is in section A—B moving away from the floating relay F, this 70 relay will close when the train reaches a certain point in the section and will thereafter remain closed even though the resistance of the shunt created by the train may increase, because the shunt around impedance 75 9 is then closed at contact 10 and so the amount of current supplied to the relay winding is materially increased.

Contact 12 of relay R and contact 11 of relay F may be used to control any desired governing means, such, for example, as a 80 railway signal or a circuit for supplying train governing energy to the track rails.

Referring now to Fig. 2, the impedance 9 is in this view included in series with the primary 4 of the track transformer T, and 85 is shunted by a low resistance path including front contact 10 of the floating relay F. When contact 10 is closed, the amount of current supplied to the winding of relay F is relatively large, and when this contact is 90 open the amount of current supplied to the winding of relay F is relatively small, and so the operation of the apparatus shown in Fig. 2 is the same as that of the apparatus 95 shown in Fig. 1.

Referring now to Fig. 3, the section A—B shown in this view is provided with a center-fed track circuit comprising a track transformer T located at the middle of the section and two track relays R, R located at the 100 two ends of the section, respectively. Winding 6 of each relay R is connected with the track rails, and winding 7 of each of these relays is constantly supplied with current from an adjacent transformer L. In this view an impedance 9 is connected in series 105 with winding 7 of each relay R, and each impedance 9 is provided with a low resist-

2

ance shunt which includes a front contact 10 of the associated relay. Assuming that a train moving toward the left passes through section A—B, track relay R at the left-hand 5 end of the section will open when the train reaches a point a short distance to the right of transformer T, whereupon the amount of current supplied to the winding 7 of this relay will become materially reduced, so that 10 the relay will remain open even if the shunt across the track rails due to the wheels and axles of the train momentarily increases in resistance. Similarly, when a train moving toward the right reaches a point a short distance 15 to the left of transformer T, relay R at the right-hand end of the section will open and will thereafter remain open even though the resistance of the train shunt increases momentarily.

20 Obviously, the resistance 9 in Fig. 3 may be interposed between relay winding 6 and a track rail, as shown in Fig. 1.

Although I have herein shown and described only three forms of apparatus embodying my invention, it is understood that 25 various changes and modifications may be made therein within the scope of the appended claims without departing from the spirit and scope of my invention.

30 Having thus described my invention, what I claim is:

1. In combination, a section of railway track, a source of current connected across the rails of said section, a relay connected 35 across the rails of said section through an impedance, and a shunt around said impedance including a front contact of said relay.
2. In combination, a section of railway track, a track circuit for said section including a source of current connected across the rails at one end and a track relay connected across the rails at the other end, a floating relay having a winding connected across the rails of said section adjacent the 45 first mentioned end through an impedance, and a shunt around said impedance including a front contact of said floating relay.
3. In combination, a section of railway track, a track circuit for said section including a source of current connected across the rails at one end and a track relay connected across the rails at the other end, a floating relay having a winding connected across the rails of said section adjacent the first mentioned end an impedance included in series 50 with a winding of said floating relay, and a shunt around said impedance including a front contact of said floating relay.

4. In combination, a section of railway track, a source of current connected across the rails of said section, a relay having a winding connected across the rails of said section, an impedance in series with a winding of said relay, and a shunt around said impedance including a front contact of said 60 relay.

5. In combination, a section of railway track, a source of current connected across the rails of said section, a relay having a winding connected across the rails of said section, an impedance connected in series with said source, and a shunt around said impedance including a front contact of said 70 relay.

6. In combination, a section of railway track, a source of current connected across the rails of said section, a relay having a winding connected across the rails of said section, an impedance for limiting the amount of current received by said relay, 80 and a shunt around said impedance including a front contact of said relay.

7. In combination, a section of railway track, a track circuit for said section including a source of current and a track relay, an impedance in series with a winding of said relay, and a shunt around said impedance including a front contact of said 85 relay.

8. In combination, a section of railway track, a track circuit for said section including a source of current and a track relay, an impedance for limiting the amount of current received by said relay, and a shunt around said impedance including a front contact of said relay. 90

9. In combination, a section of railway track, a source of current connected across the rails of said section, a relay having a winding connected across the rails of said section, and means controlled by said relay 100 for supplying a smaller amount of current to the relay when the relay is open than when the relay is closed.

10. In combination, a section of railway track, a track circuit for said section including a source of current connected across the rails at one end and a track relay connected across the rails at the other end, a floating relay having a winding connected across the rails of said section adjacent the first mentioned end and means controlled by said floating relay for supplying a smaller amount of current thereto when the floating relay is open than when it is closed. 105

In testimony whereof I affix my signature.
HENRY S. YOUNG.
